UNITED STATES PATENT OFFICE

123,295

DESIGN FOR A TOY VACUUM CLEANER

Frank E. Kinsella, Chicago, Ill., assignor to Allen
L. Atkins, Chicago, Ill.

Application August 30, 1940, Serial No. 94,730

Term of patent 7 years

To all whom it may concern:

Be it known that I, Frank E. Kinsella, a citizen of the United States, residing at Chicago, in the county of Cook and State of Illinois, have invented a new, original, and ornamental design for a Toy Vacuum Cleaner, of which the following is a specification, reference being had to the accompanying drawing, forming part thereof.

I claim:

The ornamental design for a toy vacuum cleaner, as shown.

FRANK E. KINSELLA.
